JAMES R. RICKETTS, OF RICHMOND, CALIFORNIA, ASSIGNOR TO NATIONAL AIR BRAKE SERVICE, INC., OF RENO, NEVADA, A CORPORATION OF NEVADA

TRIPLE-VALVE REAMER

Application filed July 1, 1926. Serial No. 119,907.

This invention relates to machine tools and particularly pertains to a reaming tool.

It is the principal object of the present invention to provide a tool capable of use in accurately and expeditiously reaming worn cylinder bushings of triple valves.

In carrying out this object I provide a tool which may be mounted on a triple valve. This tool is provided with an indicating mechanism for accurately aligning the tool with the cylinder bushing and for locating the lowest point therein. After the lowest point has been located, the cutting tool of the device may be quickly set and the device operated to ream the bushing.

One form which the invention may assume is exemplified in the following description and illustrated by way of example in the accompanying drawings, in which:

Fig. 1 is a central sectional view through a triple valve and a reaming tool embodying the preferred form of my invention.

Fig. 2 is an enlarged sectional view through a portion of the indicating mechanism in the head of the reaming device.

Fig. 3 is a sectional view taken on line III—III of Fig. 1.

Fig. 4 is a sectional view taken on line IV—IV of Fig. 1.

Fig. 5 is a fragmentary view in partial section through the indicating mechanism at the outer end of the tool head.

Fig. 6 is a perspective view of the tool holder.

Fig. 7 is a transverse section through the tool head taken on line VII—VII of Fig. 1 and disclosing the mechanism for taking up wear between the tool head and the mandrel.

Referring more particularly to the accompanying drawings, 10 indicates a triple valve body of any standard design and in connection with which a reaming tool, generally indicated at 11, is capable of use. This reaming tool 11 which comprises the invention is designed for the purpose of reaming the bore of a cylinder bushing 12 in the valve body 10 after the same has become worn. It will be noticed from Fig. 1 of the drawings that the cylinder bushing 12 is disposed at one end of the valve body 10 and communicates with an

elongated valve chamber 14 which extends between the cylinder bushing 12 and the opposite end of the valve body 10. The valve chamber 14 is considerably smaller in cross sectional area than the bore of the cylinder bushing 12, forming a shoulder between the two as indicated by the numeral 15.

The reaming tool 11 comprises a tool carrying head 16 which is substantially cylindrical and is formed with a centrally located bore 17, by means of which it is turnably and slidably mounted on what I prefer to term a mandrel 18. The fit between the mandrel and the tool head 16 is a running fit so that the tool head 16 will be accurately held in axial alignment with the mandrel.

In order to provide adjustment for taking up any wear occurring between the head and the mandrel, the head 16 is formed with a pair of radial openings indicated at 16^a. Reciprocably mounted in the inner end of each opening 16^a is a plug which bears against the mandrel. At the outer end of each opening 16^a a threaded plug is inserted. An adjustment screw 16^b is threaded through this plug and bears against the end of the reciprocable plug. It is obvious that by taking up on this adjustment screw 16^b the reciprocable plugs will bear against the mandrel and take up any wear which may occur.

The mandrel 18 is formed with a shoulder 19 intermediate its ends, which is of greater cross sectional area than the chamber 14 so that it will abut against the shoulder 15, while the end 20 of the mandrel will project within the valve chamber 14, as disclosed in Fig. 1.

This end 20 of the mandrel is fitted with a projecting stud 21. One end of this stud is threaded into the end of the mandrel 18 in axial alignment therewith. The opposite end projects through the chamber 14 and is threaded to receive a clamping nut 22. Turnably mounted on the stud 21 intermediate the clamping nut 22 and the mandrel 18 is a collar 23, which is formed a cross sectional area greater than that of the chamber 14, so that it may abut against the end of the valve body 10 over the end of the chamber 14. This collar 23 is formed with flat sides

24 against which thumb screws 25 abut. These thumb screws 25 are arranged at right angles to the axis of the mandrel 18, and are threaded through a sleeve 26. This sleeve 26, when the reaming tool is used, is 5 threaded onto a sleeve-like portion 27 at the end of the triple valve. By means of the thumb screws 25, it is obvious that the center of the mandrel may be adjusted to axially align it with the center of the cylinder bushing 12, prior to the tightening of the nut 22 which will clamp the valve body between the shoulder 19 on the mandrel and the collar 23 and rigidly hold the mandrel in place relative to the bore of the cylinder bushing 12. 10

15 In the present device I have provided what I prefer to term an indicator mechanism, the purpose of which is to locate the center of the bushing 12 so that the tool may be accurately aligned therewith, and to locate the low spots in the bore of the bushing so that the cutting tool may be accurately set to ream the bushing. This indicator mechanism is disclosed in Figs. 1 and 4 of the drawings, 20 and comprises a cylindrical guide member 28 extending transversely within one side of the tool head 16 flush with the outer periphery of the head, in which position it is secured by a set screw 29. Arranged transversely of the guide member 28 is a swivel pin 30. Arranged in the bore of the guide member 28 at one side of the swivel pin is a ball 31. Extending through this ball and fixed in the swivel pin 30 is an indicator pin 32, which extends co-axially of the head 16 through an aperture 33 therein to a point beyond the outer end of the head 16. 25

30 Arranged at one side of the ball 31 within the bore of the guide member 28 is a 40 feeler member 34. The outer end of this feeler member 34 is reduced in diameter and projects through the reduced end of the bore in the guide 28. The shoulders resulting from the differences in diameters at the outer 45 end of the guide member 28 prevents the feeler member 34 from projecting outwardly beyond its limit. At the inner side of the ball 31 and in the bore of the guide member 28 is a spring-pressed member 35, between 50 which and the head is interposed an expansion spring 36, the action of which constantly tends to force the feeler member 34 outwardly from the periphery of the tool head 16. It is seen that the faces of the feeler member 55 34 and the spring-pressed member 35 which engage the ball are concave so that reciprocal movement of the feeler member 34 will act through the ball 31 to oscillate the indicator pin 32, due to the fact that the 60 end of this indicator pin 32 is anchored in the transverse swivel pin 30 in the guide member 28.

65 Due to the differences in distance between the center of the feeler member 34 and the pivotal point of the pin 32, and between the

center of the feeler member 34 and the outer end of the pin 32, very slight movement of the feeler member 34 will impart considerably greater movement to the outer end of the pin 32. At this latter end the pin 32 connects with an indicator hand 37, which lies at the end of the tool head 16 and pivoted thereto at a point indicated by the numeral 38. The point of connection between the oscillating pin 32 and the hand 37 is eccentric relative to the pivotal point of the hand, so that oscillating movement of the pin 32 will cause swinging movement of the hand. This point of connection is also closely adjacent to the pivotal point of the hand so that comparatively small movement of the oscillating pin 32 will impart considerable movement to the indicating end of the indicator hand. 70 75 80

85 Also arranged on the end of the tool head 16 and beneath the indicator hand for cooperation therewith is a calibrated scale 40. This scale is pivotally mounted about the pivotal point of the hand at one end and at the other end is provided with a slotted 90 opening through which a clamping screw 40a extends into the head. By loosening this screw, the dial may be set radially with respect to the indicator hand, and held in such position by means of the clamping screw. 95 A spring 39 is connected with the hand 37 and cooperates with the spring 36 and the guide 28 to take up any lost motion occurring between the parts. 100

105 From the foregoing it is obvious that by the use of the feeler and indicating mechanism just described that when the mandrel 18 is located exactly centrally of the bushing 12, that by rotating the tool head 16 the low spots in the bore of the bushing 12 will be indicated on the scale 40 by the hand 37, and thus the lowest spot in the bore of the bushing may be easily and quickly located. Likewise, should the mandrel 18 not be in the center, by the use of the indicator mechanism 110 the center may be readily located, and the mandrel clamped in place relative to the valve body. 115

120 To accomplish this latter operation, the triple valve is set on end with the bushing uppermost and the reaming tool is mounted on the valve with its mandrel extending therethrough. The mandrel is then loosely clamped to the valve by means of the nut 22. The tool head 16 is then slowly revolved 125 by means of the crank handle 41 and the different positions of the hand 37 on the scale 40 is noted at diametrically opposite points. The difference of the reading of these points is then divided and the thumb screws 25 are 130 actuated to properly align the mandrel with respect to the axis of the bushing. It is seen that when the feeler member is at the point closest to the tool head that if the actuating screws were released, the spring pressure be- 135

hind the feeler member will cause the tool head to move toward the center. During this time the indicating hand is watched to see that the distance that the feeler member moves the head 16 is half the difference of the maximum reading between the two diametrically opposed points. When this operation is done at various different diametrically opposed points of rotation of the head 16, the tool head 16 may revolve without any movement of the hand 37, indicating that the center of the bushing has been found.

After the center has been found the calibrated scale 40 may be swung about its pivotal point so that the indicator hand will indicate zero thereon. This will permit the amount of wear in the bushing to be accurately determined as will hereinafter be described.

As before stated the tool is principally designed for reaming the bushing 12 and to this end the head 16 is formed with a cylindrical recess 42 disposed at a point diametrically opposite the feeler mechanism 34. This cylindrical recess 42 slidably receives a tool carrier 43 which is provided with a cylindrical shank 44 (see Fig. 6) which projects within the recess 42. An expansion spring 45 is interposed between the tool carrier 43 and the tool head 16 and normally tends to force the latter outwardly. The tool carrier 43 is formed with a tool socket for receiving a cutting tool 46, which when the tool carrier is arranged on the tool head projects radially. The tool 46 may be clamped in its socket in the tool carrier 43 by means of a set screw 47. Likewise, the tool carrier as a whole may be clamped in place with respect to the tool head by means of a tool clamping screw 48.

During the time that the feeler mechanism 34 is employed in correctly aligning the device relative to the center of the bushing 12, the tool holder 43 is clamped by means of the screw 48 in a position maintaining the tool 46 out of engagement with the bore of the bushing 12. After the center of the bushing has been found, and the mandrel is stationarily positioned in axial alignment therewith, the feeler mechanism is employed for locating the lowest point in the bushing 12. In performing this operation, the tool head 16 is rotated and moved axially of the bushing 12 until the lowest point is found by the feeler 34. This will be visibly indicated on the dial 40. When this low point has been found, the tool head 16 is revolved one-half of a revolution so as to bring the tool 46 in alignment with the low spot in the bore of the bushing 12. The tool clamping screw 48 is then released to permit the spring 45 to force the tool holder 43 outwardly to engage the tool 46 with the bore of the bushing. The tool clamping screw 48 is then tightened to clamp the tool holder 43 in this

position and maintain the tool 46 in cutting position. The tool head 16 is then actuated to ream the bushing. During this operation the tool head is automatically fed axially.

To accomplish this, the upper end of the mandrel 18 is counterbored and is fitted at its uppermost end with a feed nut 49. This nut is stationarily secured in the upper end of the mandrel 18 and threadedly receives a feed screw 50. This feed screw 50 extends through the feed nut into the counterbore in the mandrel 18 and is fitted at its lower end with a plunger 51. A running fit being provided between the plunger 51 and the counterbore in the mandrel 18.

The counterbore in the mandrel 18 in reality comprises an oil reservoir and the feed nut 49 and the plunger 51 are each provided with circulating ports so that reciprocable movement of the plunger caused by axial movement of the head 16 with respect to the mandrel 18 will maintain a film of oil between the contacting surfaces of the head 16 and the mandrel 18. This film of oil prevents chattering of the device when in operation.

At its upper end the head 16 is formed with a shank 52 of reduced diameter. This shank 52 is exteriorly threaded and receives a clamping cap 53. A shoulder 54 is formed on the feed screw 50 and nests within a counterbore formed in the underside of this cap 53. The cap 53 is formed with a shank 55 of reduced diameter and which is exteriorly threaded to receive a clutching nut 56. This shank 55 of the cap 53 is formed with a tapered end which is split so that when the tapered bore in the clutch nut 56 is engaged therewith, it will be contracted to grip the feed screw. This will cause the feed screw and the tool head to revolve as a unit and relative to the feed nut 49 in the upper end of the mandrel 18.

Therefore, when reaming the bushing 12, the clutch nut 56 is utilized to clamp the feed screw and tool head 16 together so that rotation of the tool head 16 will advance or retract the tool head 16 through the bushing 12 as the feeler revolves. It should be stated here that the feed screw 50 is formed with a very fine thread, so that an extremely fine cut is taken.

It is seen that the direction which the tool head 16 travels when in operation depends entirely upon its direction of rotation and that it can be run in and out through the bushing as desired. When coming to the end of a cut, the feed screw may be given a partial turn by means of the knob 57 thereon, so that upon the return cut the tool will not travel in the same path upon its return.

In operation of the device, the triple valve is set on end and the tool is mounted thereon, as previously described. The head 16 is then revolved, and by means of the indicating mechanism the tool is accurately centered, after which the nut 22 is tightened to firmly

clamp the tool on the valve. During this operation the tool head 16 is disengaged from the feed screw so that it may be revolved as desired. After being properly centered, the tool head 16 is both rotated and reciprocated through the bushing to locate the lowest point therein. This may be determined by closely watching the indicator mechanism, which will accurately indicate any movement of the feeler member.

10 It is understood that during this period the cutting tool is held in inoperative position. After locating the lowest point in the bushing, the mandrel is revolved one-half of a revolution to place the cutting tool in alignment with the lowest point in the bushing. The tool clamping screw is then released to permit the cutting tool to engage the bore of the bushing. The cutting tool is then clamped in position.

15 It is understood that this cutting tool will cut regardless of the direction of rotation of the tool head 16, so that after locating the lowest point in the bushing, the tool head 20 may be operated by the handle and feed screw to run the cutting tool in both directions through the bushing to accurately ream the same. After the end of one cut, the feed screw may be manipulated by hand so that 25 the tool may not travel in the same path when taking the second cut.

25 While I have shown the preferred form of my invention, it is to be understood that various changes may be made in its construction by those skilled in the art, without departing from the spirit of the invention, as 30 defined in the appended claims.

35 Having thus described my invention, what I claim and desire to secure by Letters Patent 40 is:

45 1. A triple valve reaming tool comprising a mandrel adapted to extend axially through a triple valve body and be clamped thereto, a tool head mounted on said mandrel and capable of rotary and axial movement thereon, said head adapted to be inserted within the cylinder bushing of the valve body for operation therein, indicating means carried by the tool head and adapted to constantly engage the bore of the cylinder bushing when 50 the head is positioned therein, said indicating means including a calibrated scale and a cooperating indicator hand arranged on the tool head at a visible point to indicate the 55 differences in diameter of the bore of the bushing at different points therealong or the amount of eccentricity of the head with relation to the bore when the head is revolved and moved axially of the bushing, a cutting 60 tool carried by the head and normally held in an inoperative position during the operation of the indicating means, means for positioning and maintaining said tool in an operative position without removing the head 65 from the bushing after the head has been cen-

tered and the low spot located in the bushing.

2. A triple valve reaming tool comprising a mandrel adapted to engage a triple valve, a tool head mounted on the mandrel for rotary and axial movement, a movable feeler member carried by the tool head and adapted to be spring-pressed into engagement with the bore of the cylinder bushing when the head is arranged within the bushing, indicating means arranged on the portion of the head visible when the head is in the bushing, an operative connection between the feeler member and the indicating means whereby the latter will visibly indicate the movement of the feeler and translate the motion of the same into measured distances to indicate the amount of eccentricity of the head relative to the bore of the cylinder bushing or differences in diameter of the bore at different points therealong, a cutting tool carried by the head and normally held in an inoperative position during the operation of the indicating means, means for positioning and maintaining said tool in an operative position without removing the head from the bushing after the head has been centered and the low spot located in the bushing.

3. A reaming tool for triple valves comprising a mandrel adapted to extend axially through the triple valve body and be clamped thereto co-axially with the cylinder bushing, a tool head mounted for rotary and axial movement on the mandrel, a feeler member arranged transversely of the head and projecting radially outwardly from the exterior surface thereof whereby it will engage the bore of the cylinder bushing when the head is positioned within the bushing, spring means constantly tending to maintain the feeler member in its outermost position against the bore of the cylinder bushing whereby the feeler member will follow the contour of the bore, said head being formed with an axially arranged recess projecting inwardly from its outermost end at an eccentric point relative to its center, an indicating pin disposed within said recess and pivoted at its innermost end to the head, a connection between the feeler member and said pin whereby movement of the former will be transmitted to the pin, a calibrated scale at the outermost end of the head, an indicator hand cooperating therewith, a connection between the hand and the pin whereby movement of the feeler member will be transmitted through the pin to the hand and the amount of movement of the feeler member indicated in measured quantities on the scale by the hand.

4. A reaming tool for triple valves comprising a mandrel adapted to extend axially through the triple valve body and be clamped thereto co-axially with the cylinder bushing, a tool head mounted for rotary and axial movement on the mandrel, a feeler member arranged transversely of the head and project-

ing radially outwardly from the exterior surface thereof whereby it will engage the bore of the cylinder bushing when the head is positioned within the bushing, spring means 5 constantly tending to maintain the feeler member in its outermost position against the bore of the cylinder bushing whereby the feeler member will follow the contour of the bore, said head being formed with an axially 10 arranged recess projecting inwardly from its outermost end at an eccentric point relative to its center, an indicating pin disposed within said recess and pivoted at its innermost end to the head, a connection between 15 the feeler member and said pin whereby movement of the former will be transmitted to the pin, a calibrated scale at the outermost end of the head, an indicator hand cooperating therewith, a connection between the hand 20 and the pin whereby movement of the feeler member will be transmitted through the pin to the hand and the amount of movement of the feeler member indicated in measured quantities on the scale by the hand, a cutting 25 tool carried by the head and normally held in an inoperative position during the operation of the indicating means, means for positioning and maintaining said tool in an operative position without removing the head 30 from the bushing after the head has been centered and the low spot located in the bushing.
